UNITED STATES PATENT OFFICE.

ANSHELM BURTON ELMSTROM, OF WORCESTER, MASSACHUSETTS.

SHOE-STRETCHER.

1,318,651.

Specification of Letters Patent. Patented Oct. 14, 1919.

Application filed February 12, 1919. Serial No. 276,690.

To all whom it may concern:

Be it known that I, ANSHELM BURTON ELMSTROM, a citizen of the United States, residing at Worcester, in the county of Worcester and State of Massachusetts, have invented a new and useful Shoe-Stretcher, of which the following is a specification.

This invention relates to a shoe stretcher of the general type in which two separable last blocks are mounted for a relative movement of separation.

It is the object of my invention to improve the construction of such shoe stretchers to the end that they may be more efficiently operated and that they may be less subject to breakage and accident.

With this general object in view, an important feature of my invention relates to improved devices for holding the rear ends 20 of the blocks in their normal relative position while permitting angular separation of the front ends thereof.

A further feature relates to the provision of anti-friction devices between the separating wedge and the last blocks by which provision ease of operation is assured. Another feature relates to the provision of a new and effective spring for drawing the blocks toward each other.

My invention further relates to arrangements and combinations of parts hereinafter described and more particularly pointed out in the appended claims.

A preferred form of my invention is shown in the drawings, in which—

Figure 1 is a side elevation of my improved shoe stretcher;

Fig. 2 is a side elevation of one part of the stretcher with certain details shown in section;

Fig. 3 is a plan view of the stretcher;

Fig. 4 is a rear elevation of the threaded nut by which the last blocks are held in position;

Fig. 5 is a plan view of the separating wedge;

Fig. 6 is a detail sectional view taken along the line 6—6 in Fig. 2 and showing my improved spring, and

Figs. 7 and 8 are detail sectional views showing modifications, taken in a position corresponding to the line 7—7 in Fig. 3.

Referring to the drawings, I have shown a shoe stretcher comprising last blocks 10 and

11 each grooved on its inner side, as indicated by dotted lines at 12 in Fig. 3, to receive a wedge 13 mounted upon a threaded rod 14 having a bearing in a nut 15. The nut 15 is provided with laterally extending portions 16 (Fig. 4) received in recesses in the inner faces of the blocks 10 and 11, and preventing relative longitudinal movement thereof. The nut 15 is also provided with an integral flange 17 at its rear end in which are mounted studs 18 extending into recesses in the rear faces of the blocks 10 and 11, and preventing lateral separation thereof.

The portions 16 of the nut 15 are somewhat loosely fitted in the corresponding recesses in the blocks and permit a relative angular separation of the blocks substantially about the rear ends thereof as axes. These recesses are formed from the inner faces of the blocks and do not extend through the outer surface.

A U-shaped spring 20 (Fig. 6) is inserted in openings 21 extending into the blocks 10 and 11 from the rear and preferably diverging, as shown in Fig. 6. Additional recesses 22 at the extreme end of the blocks receive the intermediate coiled portion of the spring, and the spring is retained in position by the flange 17 of the nut 15 which covers the recesses 22. When removed from the blocks, the two arms of the spring are normally closely adjacent, being displaced outwardly when inserted in the openings 21 and yieldingly forcing the blocks toward each other.

In Fig. 5 I have shown an improved means for securing the wedge 13 in position on the rod 14. As indicated in said figure, the rod 14 has a bearing in a hole in the rear part of the wedge 13, the end of the rod preferably being seated against an anti-friction thrust bearing 23. The rod 14 extends across an opening 24 in the wedge, and the stock of the rod is expanded in said opening as shown in Fig. 5, thus preventing displacement of the parts when once assembled.

In order to provide a more easy operation of my improved stretcher, I have shown several forms of anti-friction devices interposed between the wedge 13 and the blocks 10 and 11. In Figs. 2, 3 and 5 I have indicated rolls 25 pivoted in the wedge 13 and preferably engaging metal plates 26 secured in the

bottoms of the recesses 12 in the blocks 10 and 11. By this construction the smoothness and ease of operation is much improved.

In Fig. 7 I have shown a modification in which rolls 27 are pivoted in a casing 28 fixed in a recess in each last block, said rolls being engaged by the convex surface of the wedge 13.

In Fig. 8 a somewhat similar construction is shown in which balls 30 are substituted for the rolls 27, and it will be understood that similar substitution of balls for rolls may be made in the form shown in Fig. 5.

With the parts thus constructed, it will be evident that my improved shoe stretcher can be assembled without the use of screws or other holding devices, and that when once assembled the parts cannot be displaced except by angular separation far beyond any position assumed in normal operation.

Having thus described my invention, and certain modifications thereof, it will be evident that other changes and modifications can be made therein by those skilled in the art, within the scope of my invention as set forth in the claims, and I do not wish to be otherwise limited to the details herein disclosed, but what I claim is:—

1. A shoe stretcher having, in combination, a pair of last blocks, a block-separating screw, and a nut for said screw, said nut having portions extending laterally into said blocks and having additional portions extending longitudinally into said blocks whereby relative lateral or longitudinal displacement of said blocks is prevented.

2. A shoe stretcher having, in combination, a pair of last blocks, a block-separating screw, and a nut for said screw, said nut having portions extending laterally into said blocks and having a flange at its rear end with lugs thereon extending forwardly into

the rear ends of said blocks to prevent relative lateral or longitudinal displacement thereof.

3. A shoe stretcher having, in combination, a pair of last blocks, a block-separating screw, and a nut for said screw effective in itself to limit relative movement of said blocks to angular movements of separation substantially about the rear ends of said blocks as axes.

4. In a shoe stretcher having a pair of last blocks, means to separate said blocks, comprising a threaded rod, a nut for said rod, and a wedge having a transverse opening therein and mounted on said rod in engagement with said blocks, said rod having a bearing in said wedge and extending beyond said bearing into said transverse opening in said wedge, and an integral portion of said rod being expanded in said opening and effectually preventing relative axial displacement of said rod and wedge, while permitting relative angular movements thereof.

5. A shoe stretcher comprising a pair of angularly separable last blocks, having forwardly extending recesses in their rear ends, and a spring for said blocks having a general U-shape and having its two ends inserted from the rear in said recesses.

6. In a shoe stretcher, in combination, a pair of angularly separable last blocks having forwardly extending diverging recesses in their rear ends, and a spring for said blocks having a general U-shape and comprising a coil of wire having two straight ends extending forwardly and received in said recesses in the rear of said blocks to yieldingly resist separation of said blocks.

In testimony whereof I have hereunto affixed my signature.

ANSHELM BURTON ELMSTROM.
